135,550

DESIGN FOR A COMBINATION LAMP, PERPETUAL CALENDAR, AND CONTAINER

Edward Lee Jones, Richmond, Va.

Application December 15, 1942, Serial No. 109,038

Term of patent 7 years

To all whom it may concern:

Be it known that I, Edward Lee Jones, a citizen of the United States, residing at Richmond, in the State of Virginia, have invented a new, original, and ornamental Design for a Combination Lamp, Perpetual Calendar, and Container, of which the following is specification, reference being had to the accompanying drawing, forming part thereof.

In the drawing:

Figure 1 is a front elevational view of a combination lamp, perpetual calendar, and container, showing my new design.

Figure 2 is a front elevational view of the same with the cover of the container compartment lifted.

The opposite side is substantially the same as shown in Figures 1 and 2 and the device is circular in horizontal section throughout its height.

I claim:

The ornamental design for a combination lamp, perpetual calendar, and container, as shown and described.

EDWARD LEE JONES.
